Application October 15, 1952, Serial No. 314,832

Claims priority, application Netherlands October 24, 1951

5 Claims. (Cl. 210—24)

The present invention relates to a process of converting substances which are ionized in solution (i. e., bases, acids, salts) with the help of ion exchangers and, more particularly, the invention pertains to a method of regenerating the ion exchanger used in this conversion process.

Field of invention

It has previously been proposed to cause the conversion of two soluble salts B_1A_1 and B_2A_2 , with the help of ion exchangers, to proceed in such a manner that two different salts B_1A_2 and B_2A_1 are obtained according to the equation:

In order to realize this conversion, an ion exchanger, hereinafter denoted by the abbreviation I.E., is utilized which contains the ion B_1 and is capable of exchanging this ion B_1 for the ion B_2 , when a salt solution in which the ion B_2 is present is led over the I.E.

The first phase of the process, the so called "loading" of the I.E., may be represented by the equation:

The I.E., which is now charged with B_2 ions, is subsequently washed with water and thereafter regenerated by passing a solution of the salt B_1A_1 over it.

The second phase of the conversion process, the so-called regeneration of the I.E., may be represented by the equation:

By addition of the equations (2) and (3) supra, it will be seen that a double conversion is obtained between the salts B_1A_1 and B_2A_2 , as a result of which the salts B_1A_2 and B_2A_1 are formed, the I.E. having only functioned as an ion carrier.

In the prior procedures which have been carried out according to the Equations (2) and (3) above, (see C. r. 193, T 1013, Dutch Pat. Spec. 40,637, French Pat. Spec. 773,973) only part of the capacity of the I.E. has been utilized and in order to make the greatest possible use of the I.E., an excess of regenerating agent has most frequently been used. The necessity of doing this lies in the fact that the behavior of the I.E. with respect to the B_1 ions to be exchanged differs in its behavior with respect to the B_2 ions, this difference being due to the fact that the ion B_2 is more firmly bound to the I.E. than the ion B_1 , so that the "regeneration" of the I.E. is more difficult than the "loading" thereof.

By the term "loading" of the I.E., as used in this specification and the appended claims, is to be understood the process in which the I.E. containing a particular ion is contacted with a solution containing another ion which it is desired to substitute for the ion of the I.E. and which is more firmly bound by the I.E. than the one which the I.E. is to release. The term "regeneration," as used in the specification and claims, stands for the process wherein the I.E. loaded with a particular ion obtained from a solution with which the I.E. has been treated, is con-

tacted with a regenerating solution containing another ion which in all, or in part, of the mixing ratios in which the two ions may be present side by side in the solution, is less firmly bound by the I.E. than the ion with which the I.E. is loaded.

Thus, for instance, if it is assumed that the ion B_2 is more firmly bound by a certain I.E. than the ion B_1 , the result will be that the loading according to the equation

in a limited number of columns arranged in series and filled with $B_1.I.E.$, can be carried out in such a manner that a pure B_2A_2 solution fed at one end of the series of columns can always be discharged at the other end as a pure B_1A_2 solution.

With such a load, it appears that a stationary transition zone moves through the columns, so that on the feeding side of this zone, the solution present in the columns and the I.E. contain exclusively B_2 ions, and the solution and the I.E. at the discharge side of this zone contain exclusively B_1 ions, whereas in the transition zone itself, the proportion

$$\frac{B_2}{B_1 + B_2}$$

in the solution and on the I.E. gradually changes, during which process all the proportions between 1 and 0 are traversed.

However, the length of this transition zone is constant and the dimensions of the columns are always chosen so that the whole transition zone lies within one column or a few columns.

In a regeneration process according to the equation:

it will be seen that such a stationary transition zone of constant length will not be formed. That is, if an I.E. contained in a number of columns arranged in series and loaded with the firmly bound B_2 ions is regenerated by adding to the first column a solution of the ion B_1 , which is less firmly bound by the I.E. than the B_2 ion, the transition zone formed in the column moves and also keeps increasing in length. Only by means of a constantly increasing number of columns can the solution present in the columns and the I.E. itself on the feeding side of this transition zone be made to contain exclusively B_1 ions and at the other side of this zone the solution and the I.E. to contain exclusively B_2 ions, while over the length of the transition zone and in the direction of the liquid current the proportion

$$\frac{B_2}{B_1 + B_2}$$

changes from 0 to 1.

In technical practice, however, it is only possible to carry out the continuous regeneration process in a limited and constant number of columns arranged in series. It follows, therefore, that in the regeneration carried out in this manner, it is impossible to obtain both a complete regeneration and a liquid discharging from the last of the series of columns consisting exclusively of a solution of the cation B_2 , which means that in all cases, a solution is obtained in which the proportion

$$\frac{B_2}{B_1 + B_2}$$

is, on an average, <1 . As a result, the regeneration has been carried out with an excess amount of regenerating solution containing the ion B_1 with respect to the amount of $[B_2.I.E.]$ regenerated. Such use of an excess of regenerating solution is not a drawback, provided the regenerating agent is an inexpensive salt, the

solution of which as such is obtainable in large amounts. For instance, the previously proposed preparation of NaNO_3 by converting a $\text{Ca}(\text{NO}_3)_2$ solution with sea water with the help of an I.E. can be effected economically without recovering the regenerating agent NaCl . In this case, the solution obtained in the regeneration is nothing but sea water which has become poor in NaCl and has some CaCl_2 dissolved therein. Such a solution contains no valuable components and may, therefore, be directly pumped into the sea without objection.

However, in the corresponding preparation of KNO_3 , by converting a $\text{Ca}(\text{NO}_3)_2$ solution and a KCl solution, the liquid discharging from the last column during the complete regeneration of the I.E. loaded with Ca ions, contains, besides CaCl_2 , a considerable amount of KCl and this liquid cannot, therefore, be considered worthless.

It has now been found possible to carry out the complete regeneration of the I.E. in a limited number of columns in such a way that the liquid leaving the last column contains a virtually pure solution of only one salt. Thus, when making KNO_3 , by converting solutions of $\text{Ca}(\text{NO}_3)_2$ and KCl , it is possible to obtain, according to the invention, a final liquid consisting of a virtually KCl -free CaCl_2 solution, by regenerating with a KCl solution an I.E. loaded with Ca ions. Furthermore, little or none of the KCl used as regenerating agent is lost.

Objects

The principal object of the present invention is the provision of a novel method for the regeneration of ion-exchangers, or columns filled with such ion-exchangers, which method is free from the disadvantages noted above in connection with prior regeneration techniques.

Other objects include:

(a) The provision of an improved method for the regeneration of a series of columns containing the ion-exchanger to be regenerated, whereby substantially completely regenerated ion-exchanger columns are obtained at one end of the series and a solution of spent substantially completely converted regenerating agent is obtained from the other end of the series.

(b) The provision of an improved method for the regeneration of a series of a limited but constant number of columns containing the ion-exchanger loaded with the ion to be replaced, whereby there may be obtained from the last column of the series a substantially pure aqueous solution, of a compound of the ion removed from the ion-exchanger.

(c) The provision of an improved process for the double conversion of solutions of salts, acids or bases, using a series of columns containing an ion exchanger and involving novel improvements in regenerating the ion-exchanger, whereby both completely a regenerated column and a completely converted regenerating agent are obtained.

Still further objects and the entire scope of applicability of the present invention will become apparent from the detailed description given hereinafter; it should be understood, however, that the detailed description and specific examples, while indicating preferred embodiments of the invention, are given by way of illustration only, since various changes and modifications within the spirit and scope of the invention will become apparent to those skilled in the art from this detailed description.

Description

Briefly stated, the objects outlined above are realized, in accordance with the present invention, by carrying out the regeneration phase of the conversion procedure in three successive stages, rather than in a single stage as has previously been the case, with the series of columns containing the ion exchanger to be regenerated set up into two groups.

More specifically, the present invention provides the improvements in a process for regenerating an ion-ex-

changer by passing a solution of a regenerating agent successively through a series of columns containing the ion-exchanger loaded with the ion to be replaced and withdrawing regenerated ion-exchanger from the first of the series and a solution of spent substantially completely converted regenerating agent from the last of the series, comprising the steps of dividing the series of columns into two groups and passing an excess of regenerating agent through the first group, removing excess regenerating agent from the solution discharged from the first group of columns, thereafter, passing said solution through the second group of columns, collecting the substantially completely converted regenerating solution from the last column of the second group, cutting out the first column of the first group and making the first column of the second group the last of the first group, introducing a new column filled with untreated ion-exchanger loaded with the ion to be replaced at the end of the second group and, thereafter, repeating said operation.

The regenerating method according to the invention is not only applicable to the preparation of KNO_3 by double conversion of KCl and $\text{Ca}(\text{NO}_3)_2$ solutions with the help of an ion-exchanger, but in principle, the process may be used advantageously for many double conversions between ionogenic substances, in which a series of successive loadings and regenerations of the ion-exchanger, according to the above-mentioned Equations (2) and (3) are employed, namely:

These loadings and regenerations are interrupted only by washing with water of the amount of B_2A_2 or B_1A_1 solution still contained in the free space between and in the I.E. grains.

In order that the invention may be more readily understood, the manner of carrying the invention into effect is hereinafter described with reference to the accompanying drawings, in which:

Figure 1 is a flow diagram of the regeneration, and Figure 2 is a flow diagram of the loading of the columns containing the ion-exchanger.

In Figure 1, $\text{C}_1, \text{C}_2, \dots, \text{C}_m$ represent a first group of a limited number (m) of columns arranged in series; $\text{D}_1, \text{D}_2, \dots, \text{D}_n$ represent a second group of a limited number (n) of columns arranged in series, and E_v and C_r represents, respectively, an evaporator and crystallizer arranged between the two groups of columns to be regenerated.

In Figure 2, $\text{E}_1, \text{E}_2, \dots, \text{E}_p$ represent a series of a limited number (p) of columns to be loaded.

In carrying out the regeneration process, according to the invention, a solution of B_1A_1 is admitted to the first column C_1 in the first stage and permitted to flow through the following columns C . Thus, a virtually stationary state is created in this group of columns, so that the ion-exchanger in column C_1 is fully regenerated after a certain time and, therefore, only contains $\text{B}_1\text{I.E.}$ In the remaining columns C , the ion-exchanger is to some extent regenerated with B_1 ions, but contains B_2 ions as well, in such a manner that the proportion

$$\frac{\text{B}_2}{\text{B}_1 + \text{B}_2}$$

on the ion-exchanger shows a continuous increase per column in the direction of the liquid current. Thus, the last column C_m contains an incompletely regenerated I.E. and the liquid to be discharged therefrom consists of a solution containing both B_1A_1 and B_2A_2 , in which the proportion

$$\frac{\text{B}_2}{\text{B}_1 + \text{B}_2} = y_1 < 1$$

The second stage of the regeneration consists in taking the liquid from the column C_m and freeing the same, as

for example, by evaporation and crystallization, with or without the addition of an additional substance as hereinafter described, of one or both of B_1A_1 and B_2A_2 to such an extent that in the liquid the proportion

$$\frac{B_2}{B_1+B_2}$$

is altered and brought to a value of y_2 at which $1 > y_2 > y_1$.

During the third stage, the liquid obtained in the preceding stage is fed to the first column of the group of columns D filled with ion-exchanger yet to be regenerated and arranged in series. The liquid is permitted to pass through each of the columns D, a virtually stationary state being attained in which the columns D will come to contain an ion-exchanger loaded with both B_1 and B_2 ions in such a manner that the last column D_n contains an ion-exchanger which is almost entirely unregenerated [B₂.I.E.]. From this last column D_n , a B_2A_1 solution is discharged which is virtually free from regenerating agent B_1A_1 , the preceding columns containing an ion-exchanger with an increasing degree of regeneration. This means that the proportion

$$\frac{B_2}{B_1+B_2}$$

on the ion-exchanger constantly increases from D_1 to D_n .

According to the invention, the completely regenerated column C_1 , at the side where the regenerating agent is supplied, is put out of the circuit at the end of a certain lapse of time, i. e., the "regeneration period." However, the series of columns is recompleted by adding a new column containing ion-exchanger which is completely unregenerated, the feed and discharge of the two groups of columns at the same time being subjected to an alteration such that the first column of group D is moved over to group C and becomes C_m . A new regeneration period is then begun whereby one more column, the first of the first stage, is completely regenerated.

In the transition from one regeneration period to the following one, it will be appreciated that a column at one side of the series of columns C is put out of the circuit, while at the other side a new column is added. In this way, the total number of columns subjected to a regeneration treatment per regeneration period is always the same. Thus, column C_2 will come to function as C_1 in the preceding period, column C_3 will come to function as C_2 in the preceding period, column C_m will come to function as C_{m-1} in the preceding period, column D_1 will come to function as C_m in the preceding period, column D_2 will come to function as D_1 in the preceding period, etc. D_n will come to function as D_{n-1} in the preceding period, and the new column added will come to function as D_n in the preceding period.

At the end of the subsequent regeneration period, column C_2 is put out of the circuit and the other columns are again rearranged with the addition of still another new column in the manner denoted above.

The success of the invention is due, at least to a large extent, to the splitting up of the regeneration into three stages and the corresponding change effected in the composition of the solution traversing the groups of columns C and D during one regeneration period by virtue of the removal, as by crystallization, of excess regenerating agent in the second stage of the regeneration. These features make it possible to use a limited and constant number of columns to regenerate the ion-exchanger completely without the drawbacks involved if an ever-widening transition zone moving within the columns is allowed to build up and with the advantage that a simple solution of B_2A_1 virtually free from the regenerating agent B_1A_1 originally supplied to the columns can be obtained as discharge from the last column.

As to the extent the composition of the liquid is to be changed by the crystallization, this is determined by the excess of regenerating agent B_1A_1 supplied to the group

of columns C per regeneration period. As already stated, every time a new regeneration period is started, a new column of [B₂.I.E.] is added and a column with an equivalent amount of [B₁.I.E.] is put out of the circuit.

When the number of ions attached to the I.E. is Q equivalents per column, and to the first column of group C an amount of regenerating agent B_1A_1 equal to kQ equivalents is fed per regeneration period, not taking into consideration the amount of solution needed for filling the free space between the grains of ion-exchanger, it is necessary to remove from the liquid discharging from the column C_m , $(k-1)Q$ equivalents of B_1A_1 by crystallization.

It occasionally happens that from the last column no solution is discharged which is substantially free from B_1A_1 , although the excess of B_1A_1 used for regeneration in the second stage of the regeneration process has been removed. In order to avoid this, it is also advisable to remove a relatively small amount of B_2 ions from the regenerating liquid in the second stage of the regeneration process. Often, however, it is not possible to remove an amount of B_2A_1 by crystallization, especially if the B_2A_1 substance is very soluble. In such cases, the desired effect can be reached by allowing an insoluble B_2 compound to form in the solution by adding, for instance, the compound B_1A_3 to a solution containing both B_1A_1 and B_2A_1 . By doing this, B_2A_3 precipitates and an equivalent amount of B_1A_1 is dissolved. This newly-formed amount of B_1A_1 should then be removed by crystallization together with the excess of B_1A_1 . The amount of B_2 ions to be removed cannot be determined exactly and must be ascertained experimentally in those cases where it is found that, after removing B_1A_1 in the second stage of the regeneration process, the solution discharged from the last column is not practically free from B_1A_1 . In practice, however, it has been found that it generally suffices to remove only a relatively small quantity of B_2 ions.

The loading of the regenerated columns may be carried out in the conventional way shown in Figure 2, i. e., by admitting a solution of B_2A_2 to the first column of a group consisting of a limited number (p) of columns (E) filled with [B₁.I.E.] and arranged in series, after which the solution is permitted to flow through the succeeding columns. In this way, a virtually stationary state is created in this series of columns (E) so that the I.E. in column E_1 is fully converted after a certain time, and therefore only contains [B₂.I.E.]. The succeeding columns contain an I.E. which is to some extent loaded with B_2 ions, but carries B_1 ions as well, such that the proportion

$$\frac{B_1}{B_1+B_2}$$

on the I.E. shows a continuous increase per column in the direction of the liquid current. Hence, the last column E_p contains a very incompletely loaded I.E., while the liquid to be discharged from this column consists of a solution of B_1A_2 .

The completely loaded column E_1 , at the side where the loading agent is supplied, is put out of the circuit at the end of a certain lapse of time, i. e., at the end of the "loading period." The series of columns is recompleted by adding a new column containing ion-exchanger which is fully regenerated, i. e., one to be "loaded," and a new "loading period" begun, in which just the first column is completely loaded.

The total number of columns subjected to a loading treatment per loading period is always the same. Thus in the new "loading" period: column E_2 will come to function as E_1 in the preceding period, column E_{p-1} will come to function as E_{p-2} in the preceding period, column E_p will come to function as E_{p-1} in the preceding period, and the new fully regenerated column added will come to function as E_p in the preceding period.

The following examples illustrate further the nature of the invention and the manner in which it may be carried into effect.

EXAMPLE I

In the preparation of KNO_3 from solutions of KCl and $\text{Ca}(\text{NO}_3)_2$ with the help of an I.E. consisting of sulfonated styrene (the normal trade product Dowex-50) use was made of columns each of which contained 100 litres of I.E. The capacity Q per column amounted to 218 equivalents CaO . The free space between the I.E. grains in the column had a volume of 40 litres.

The regeneration of the columns loaded with Ca ions was carried out in such a manner that for each regeneration period six columns were traversed by the regenerating liquid, the columns being arranged in two groups of three columns each. During one regeneration period, a 37% KCl solution was fed to the first column of the first group at 90°C . A total of 198 kg. of solution was fed to the first column. This means 3.3 Q equivalents of $\text{KCl} + 52$ kg. 37% solution, which is the 40 litres remaining behind in the free space between the I.E. grains that are removed from the cycle when the column is taken out of the system. From the third column of the first group a total amount of 196 kg. of solution was discharged, first 52 kg. present in the free space and after that 144 kg., the mean composition of which was as follows:

$$\begin{array}{l} 28\% \text{ KCl} \\ 8\% \text{ CaCl}_2 \\ 64\% \text{ H}_2\text{O} \end{array} \quad \text{i. e., } y_1 = \frac{\text{eq. Ca}}{\text{eq. Ca} + \text{eq. K}} = 0.28$$

The 196 kg. of solution were concentrated, during which process 67 kg. of water were evaporated, and the liquor subsequently cooled, so that 2.3 equivalents = 37 kg. of KCl were crystallized out. After centrifuging, the mother lye (92 kg.) of the following composition

$$\begin{array}{l} 5.5\% \text{ KCl} \\ 29\% \text{ CaCl}_2 \quad (y_2=0.88) \\ 65.5\% \text{ H}_2\text{O} \end{array}$$

was fed to the first column of the second group.

During the regeneration period first 30 litres of water were discharged from the last column of this second group (water present in the free space between the grains of I.E., which was displaced by the in-flowing regeneration liquid), after which 49 kg. of a solution having the composition

$$\begin{array}{l} 0.8\% \text{ KCl} \\ 26\% \text{ CaCl}_2 \\ 73\% \text{ H}_2\text{O} \end{array}$$

were removed.

The first column of the first group was fully regenerated and put out of the circuit, after which a new column was added to the second group and another regeneration period with six columns arranged in two groups of three columns each, was started up.

EXAMPLE II

For the preparation of NaNO_3 by double conversion of NaCl and $\text{Ca}(\text{NO}_3)_2$ use was made of the same I.E. in the same columns as described in Example I.

In the regeneration process of the I.E. loaded with Ca ions, six columns in series, arranged in two groups of three columns each, were again employed.

To the first column of the first group, a 26% NaCl solution at about 20°C . was fed in, so that for each regeneration period a total of 146.3 kg. of solution was supplied. This corresponds with 2 Q equivalents of $\text{NaCl} + 40$ litres of solution for the free space.

During this period, the first 40 litres of solution (about 48 kg.), contained in the free space, were discharged from

the third column of the first group, and then 97.8 kg. of solution with a mean composition of:

$$\begin{array}{l} 8.7\% \text{ CaCl}_2 \\ 17.0\% \text{ NaCl} \quad (y_1=0.35) \\ 74.3\% \text{ H}_2\text{O} \end{array}$$

To this solution, 4.75 kg. of Na_2CO_3 (89.6 gram equivalents) were added after which the resulting CaCO_3 precipitate (4.48 kg.) was removed by filtration. Thereafter, 10 53.6 kg. of water were removed by evaporation after which by cooling and centrifuging 18 kg. of NaCl were removed from the resulting mother lye.

The rest of the mother lye, 26.5 kg. in all and having a composition of

$$\begin{array}{l} 13.3\% \text{ CaCl}_2 \\ 14.5\% \text{ NaCl} \quad (y_2=0.49) \\ 72.2\% \text{ H}_2\text{O} \end{array}$$

was supplied to the first column of the second group, together with the 40 litres which had previously been discharged from the last column of the first group of columns. From the last column of this group first 30 litres of water were removed per regeneration period and, subsequently, 36 kg. of solution which contained only a trace of NaCl 25 along with 19.8% of CaCl_2 and 80.2% of H_2O .

A new regeneration period was started in which the column that had been totally regenerated in the preceding period was first put out of the circuit and a new column to be regenerated thereafter added.

EXAMPLE III

Magnesium chloride and potassium sulfate were prepared by double conversion of MgSO_4 and KCl with the help of the anion-exchanger consisting of a polystyrene 35 with quaternary N-groups (the normal trade product Dowex-2). While using a rather concentrated solution (>1 molar), it was found that the Cl -ion is bound more strongly by the I.E. than the SO_4 -ion, so that the regeneration may be represented by the equation:

In the same way as in the preceding examples, the columns contained 100 litres of I.E., the capacity per 45 column being $Q=100$ equivalents. The free space had a capacity of about 40 litres. Five columns were arranged in series for each regeneration period, in which arrangement the first group consisted of three and the second group of two columns.

To the first column of group one, a total of 172.5 kg. of 25% MgSO_4 solution was supplied per regeneration period. This means five Q equivalents $\text{MgSO}_4 + 52$ kg. MgSO_4 solution retained in the free space between the I.E. grains. From the third column of the first group 55 the first 40 litres (about 52 kg. of solution) present in the free space were discharged and then 119.4 kg. of solution in all, of which the mean composition was:

$$60 \text{ 20.7\% MgSO}_4 \quad \text{i. e., } y_1 = \frac{\text{eq. Cl}}{\text{eq. Cl} + \text{eq. SO}_4} = 0.18 \\ 3.6\% \text{ MgCl}_2 \\ 75.6\% \text{ H}_2\text{O}$$

The solution was evaporated to such a degree that at 25°C . 48.8 kg. of MgSO_4 were crystallized out and separated from the remaining mother lye (17.2 kg.) by 65 centrifuging. The mother lye, having the composition

$$\begin{array}{l} 25\% \text{ MgCl}_2 \\ 5\% \text{ MgSO}_4 \quad (y_2=0.86) \\ 70\% \text{ H}_2\text{O} \end{array}$$

70 was supplied to the first column of the second group of columns together with 40 litres of liquid discharged from the free space in the last column of the first group.

Per regeneration period 30 litres of water were 75 discharged from the last column of the second group after

which there were obtained 27 kg. of a solution whose composition was:

17.5% MgCl₂
1% MgSO₄
81.5% H₂O

After this a new regeneration period was started.

Summary

As will be appreciated from the foregoing, the present invention provides a new and highly advantageous process for the regeneration of columns filled with ion-exchangers, particularly those used in carrying out double conversion between two salt solutions, e. g., the double conversion between KCl and Ca(NO₃)₂ to give KNO₃ and CaCl₂.

The regeneration process of the present invention possesses the advantage of enabling complete ion-exchange regeneration using a limited and constant number of columns containing the ion-exchanger to be regenerated, while avoiding the disadvantages involved if an ever-widening transition zone moving within the columns is allowed to build up. At the same time, the present process possesses the additional advantage of permitting discharge from the regenerating columns of a single solution containing a compound of the ion removed from the ion-exchanger which is substantially free of the regenerating agent.

Furthermore, due to the new improved regenerating method described herein, it is possible to carry out a number of double conversions in a much more economical way than hitherto possible.

Having described my invention, what I claim is:

1. In a process for regenerating an ion-exchanger by passing a solution of a regenerating agent successively through a series of columns containing the ion-exchanger loaded with the ion to be replaced, wherein the series of columns is divided into a first group and a second group, and periodically the first column of said first group containing a regenerated ion-exchanger is removed from the series, the first column of said second group is made the last column of said first group, and a new

column containing untreated ion-exchanger loaded with the ion to be replaced is connected at the end of said series, the improvement which comprises passing an excess of said regenerating agent through said first group, 5 removing an amount of said regenerating agent substantially equal to that originally present as excess from the effluent discharged from said first group, and thereafter passing said effluent free from excess regenerating agent through said second group whereby a solution of spent, substantially completely converted regenerating agent is withdrawn from the last column of said series.

2. The method of claim 1, wherein excess regenerating agent is removed from the solution discharged from the first group of columns by evaporation to crystallize out the excess agent and the mother liquor freed from the resulting crystals of excess regenerating agent is fed into the second group of columns.

3. The method of claim 1, wherein a relatively small amount of the ion removed from the ion-exchanger is also removed from the solution discharged from the first stage along with the regenerating agent.

4. The method of claim 3, wherein the amount of the ion removed from the solution with the regenerating agent is precipitated by adding an equivalent amount of a compound comprising the active ion of the regenerating agent and forming an insoluble compound with the ion to be removed and, thereafter, filtering the liquid.

5. The method of claim 1 wherein the ion exchanger is loaded with Ca ions and the regenerating agent is KCl.
